UNITED STATES PATENT OFFICE.

FRANK DUTCHER, OF VERSAILLES, PENNSYLVANIA.

SIGNAL-TORPEDO.

No. 825,201.

Specification of Letters Patent.

Patented July 3, 1906.

Application filed April 13, 1905. Serial No. 255,813.

To all whom it may concern:

Be it known that I, FRANK DUTCHER, a citizen of the United States, residing at Versailles, in the county of Allegheny and State of Pennsylvania, have invented certain new and useful Improvements in Railway-Track Signal-Torpedoes, of which the following is a specification, reference being had therein to the accompanying drawings.

This invention relates to improvements in railway-track signal-torpedoes and is made of a non-metallic material for the purpose of preventing the flying of particles of metal and the consequent injury to persons who may happen to be in the path of any of these flying pieces of metal.

My present invention is an improvement upon my Patent No. 610,672, granted September 13, 1898.

One object of my present invention is the relative arrangement or direction of extension of the rail-engaging strap in respect to the torpedo, whereby the torpedo will assume a position on the track at right angles to that assumed by the torpedo in my before-mentioned patent and to thereby accomplish certain improved practical results.

Another object of my present invention is to so form the paper or non-metallic casing that contains the explosive compound that it is materially strengthened and stiffened and the resistance from the explosion materially increased and altogether thereby a more durable and efficient torpedo of the non-metallic type is provided.

A further object of my present invention is to provide an improved strengthening and stiffening covering for the paper case and to at the same time so arrange the rail-attaching strap in relation to the casing and the covering that the covering performs the additional function of uniting the rail-engaging strap in an efficient manner to the said paper casing.

A further object of my present invention is to so construct the paper casing that the rail-engaging strap is held between the casing and the covering therefor that the strap will not have any lateral movement in respect to the casing or covering.

My present invention further includes certain details of construction having in view certain objects, all of which will be fully understood from the following specification and accompanying drawings, in which—

Figure 1 is a perspective view of my im-

proved torpedo, showing it in position upon the tread of the track. Fig. 2 is a longitudinal sectional view through the center of the torpedo, also showing it in position upon the track. Fig. 3 is an under perspective view of my improved torpedo, the covering being shown in section. Fig. 4 is an under perspective view of the paper or non-metallic casing which contains the explosive compound.

In carrying out my present invention I preferably form the non-metallic casing 1 of paper. As shown, this casing is tubular in cross-section and is composed of a flat bottom 2 and a curved top 3. For the purpose of stiffening, strengthening, and increasing the effective resistance of the paper casing the longitudinal edges are preferably crimped or forced together, as shown at 4, which provides, as will be readily understood, practically longitudinally-extending stiffening-ribs owing to these flattened or crimped portions. Preferably diagonally-arranged indentations 5 are formed at the same time that the edges 4 are flattened or crimped, which adds to the stiffness, rigidity, and resisting power of the casing. The detonating compound 6 is placed within the casing 1, and the ends of the casing are suitably closed, preferably by non-metallic plugs 7, suitably cemented or otherwise secured therein.

For the purpose of adding increased strength, rigidity, durability, and resisting power to the casing 1 and for the purpose of providing a simple and efficient manner of attaching to the torpedo a rail-engaging member or strap 8 I cover the casing with a cloth or fabric 9 and place the said rail-engaging member 8 between the flat bottom of the case and the cover. For the purpose of also adding to the rigidity, durability, and strength of the completed torpedo the fabric or cloth covering 9 is passed around the casing in such a manner as to provide a double thickness of the cloth at the bottom of the case. This also provides quite a rigid holding portion for engaging the under side of the strap, and thereby more firmly holds the strap in place. This is accomplished by starting the covering at one side 10 of the bottom of the case, passing it around the case and lapping it over the end 10, and carrying it to the opposite side 11 of the case.

For the purpose of positively holding the rail-engaging member against lateral movement the flat bottom 2 of the case has pressed

therein (preferably at the same time that the crimping of the edges 4 is accomplished) a longitudinally-extending groove 12, of a suitable width to receive the rail-engaging member 8. By passing the rail-engaging member longitudinal the torpedo and having its ends extending from the ends of the torpedo it supports the torpedo in a position transverse the track, and thus presents to the approaching car-wheel a curved surface over which the wheel readily rides without any tendency to dislodge it from the tread of the rail by a rapidly-moving train, which might be the case if the torpedo is placed longitudinal the tread, and thus avoids the necessity of and the expense of a leader-strap, such as shown in my aforementioned patent. It is well known in the practice that the rails when wet become slippery and that it is necessary to properly waterproof a paper or non-metallic torpedo by a suitable external waterproofing compound and that a fast-running train striking the abrupt portion of such a torpedo will frequently slide it or knock it off of the track, thus missing the danger-signal. By making the bottom of the torpedo flat and arranging the rail-attaching member so that the torpedo is supported transverse the track with its curved portion toward the advancing car-wheel it is found in practice that the wheel will ride over the round portion of the torpedo and that the flat bottom portion will prevent the torpedo from rolling in front of the car-wheel, which would be the case if the torpedo were made of a round tube and a flat bottom portion not provided.

I do not limit myself to the details of construction herein shown, because these may be varied so far as the spirit and scope of my invention is concerned without departing therefrom.

It will be observed that the curved top provides, in effect, oppositely tapered or inclined portions, and it will be readily understood that the taper curve or incline may extend in one direction only, so far as the broad scope of my invention is concerned; and I desire to have it understood that the term "curve" in the specification and claims 50 is intended to be sufficiently generic to include such obvious variations, where not specifically defined, to prevent such an interpretation.

Having thus described my invention, what I claim, and desire to secure by Letters Patent, is—

1. A torpedo having a flat bottom and a curved top, combined with a rail-attaching member extending from opposite ends thereof and adapted to engage the tread of the rail and support the torpedo in a position transverse the rail with the curved portion toward the advancing car-wheel, and the flat portion on the tread of the rail, for the purpose described.

2. A non-metallic track-torpedo composed of a non-metallic tubular member containing the explosive compound and having a curved top and a flat bottom, and rail-engaging members extending from opposite ends of the 70 said tubular member, for the purpose described, and a covering for the tubular member and holding the strap to the under flat side thereof, substantially as described.

3. A non-metallic track-torpedo composed 75 of a tubular member containing detonating compound and having a curved top and a flat bottom, a rail-attaching strap extending longitudinal the said flat bottom and at the outer side thereof, and a cover for the tubular member also embracing the said strap for holding it in position, as and for the purpose described.

4. A track-torpedo comprising a tubular member containing a detonating compound 85 and having a curved top and a flat bottom, the outer side of the flat bottom having a longitudinal groove, a rail-engaging member located in said groove and having extending ends for engaging the rail, and a member applied to the bottom of the tubular member and inclosing the said rail-engaging member.

5. An improved non-metallic torpedo comprising a non-metallic tubular case having a curved top and longitudinally-extending 95 crimped portions, and a rail-attaching member connected therewith.

6. An improved non-metallic track-torpedo comprising a non-metallic tubular member having a curved top and a flat bottom, the said member being crimped at the junction of the curved top and the flat bottom, a detonating compound within the said tubular member, and a rail-attaching device connected to the tubular member. 105

7. An improved track-torpedo, comprising a non-metallic tubular case containing detonating compound and having a curved top and a flat bottom, a rail-engaging member applied at the outer side of the bottom, a 110 cover passing around the case and embracing said rail-engaging member, the cover overlapping at the bottom of the case to form a double thickness over the rail-engaging member. 115

8. An improved non-metallic track-torpedo, comprising a non-metallic tubular case having a flat bottom and a curved top, and a covering of cloth or fabric doubled at the bottom thereof. 120

9. An improved non-metallic track-torpedo, comprising a paper tubular case, and a cloth or fabric covering, and a rail-engaging member connected therewith.

10. An improved non-metallic track-torpedo, comprising a tubular paper case containing detonating material, a rail-engaging member, and a cloth or fabric cover inclosing the said case and securing the rail-engaging member to the case. 125 130

11. An improved non-metallic torpedo, comprising a fibrous case, a detonating compound within the case, the fibrous case itself having doubled portions constituting 5 strengthening and resisting beads or ribs.

12. An improved non-metallic track-torpedo having a case containing a detonating compound, the case composed of a fibrous material and having a flat portion, the fibrous

material being double substantially in a line 10 with the flat portion to constitute a strengthening and resisting bead or rib.

In testimony whereof I affix my signature in presence of two witnesses.

FRANK DUTCHER.
